SURGICAL SPLINT

William H. Dietsch, Collingswood, N. J.

Application November 30, 1950, Serial No. 198,425

3 Claims. (Cl. 128—87)

1

The present invention relates to a surgical splint of extremely simple and durable character, particularly adapted for first aid use.

The invention has for its purpose the provision of a telescopic splint embracing an outer and inner member which may be interlocked with the inner member so positioned as to be coextensive with the outer member and which inner member may be projected from either end of the outer member and effectively interlocked therewith in any desired position.

More specifically, it is the purpose and object of the invention to provide a telescopic splint which may be fabricated from molded plastic and which is so constructed as to have effective reinforcement in all positions of use.

Still more specifically it is the purpose and object of the invention to provide a telescopic splint embodying storage recesses wherein first aid supplies and equipment may be housed, immediately ready for use when needed.

Further and more detailed objects and purposes of the invention will become apparent as the description proceeds, wherein:

Figure 1 is a perspective view showing the telescopic members in extended relationship.

Figure 2 is a plan view showing the parts broken away and illustrating the position of the telescopic members when only partially extended.

Figure 3 is a cross-sectional view taken on the line 3—3 of Figure 2 showing the interlocking member ready to be positioned.

Figure 4 is a cross-sectional view taken on the line 4—4 of Figure 2, and

Figure 5 is a transverse cross-sectional view taken on the line 5—5 of Figure 4 with the intermediate portion broken away.

Referring to the drawings, it will be observed that the splint embraces the elongated flat hollow outer member 10 and the elongated substantially flat inner member 11 which is coextensive in length with the outer member 10. For convenience of reference, the members will be described as having upper and lower surfaces with respect to the positions occupied thereby in the drawings, though it is to be appreciated that the splint may be used with either side in engagement with the limb of the patient. The outer telescopic member 10 has parallel top and bottom walls 12 and 13. The intermediate portion of the top wall 12 is of substantially greater thickness as indicated at 14 than the thickness of the bottom wall 13. The top and bottom walls 12 and 13 of the outer member 10 are interconnected as a unitary structure by the curved side

2

wall portions 15 and 16. The inner surfaces of the side walls 15 and 16 take the form of an arc of a circle. The inner member 11 has an outer configuration conforming with the configuration of the longitudinal passageway 17 extending from end to end of the outer member 10 and defined by the upper and lower walls 12 and 13 and the side walls 15 and 16 thereof. It will be observed, therefore, that the central portion 18 of the inner member 11 has a thickness corresponding to the narrower portion of the passageway 17 and that the marginal portions 19 and 20 of the inner member 11 are so formed that they snugly fit the inner arc-like portions of the side walls 15 and 16 of the outer member 10. The marginal portions 19 and 20 of the inner member 11 are provided respectively with the longitudinally extending cylindrical storage recesses 21 and 22, the opposite ends of which threadedly receive closure plugs 23 (see Figure 5).

The means for effecting interlocking of the outer telescopic member 10 and the inner member 11 embraces the spring steel staple-like members 24 and 25, the legs 26 of which are normally tensioned toward each other. The outer member 10 is provided with a pair of openings 27 near each end thereof, one set for receiving the legs 26 of the staple-like member 24 and the other set for receiving the legs 26 of the staple-like member 25. The inner member 11 is provided with a multiplicity of pairs of openings 28 which are adapted to be brought into vertical alignment with openings 27 in the outer member 10. When a selected pair of openings 28 of the inner member 11 are in alignment with one of the pairs of openings 27 in the upper wall 12 of the outer member 10 as illustrated in Figure 3, the legs 26 of either the staple-like members 24 or 25 can be slightly spread apart and inserted through the aligned openings 27 and 28 to effectively interlock the outer member 10 and inner member 11 in a desired position of telescopic adjustment.

The upper wall 12 of the outer member 10 is conveniently cut away as indicated at 29 and 30 to provide thumb and finger access to the staple-like members 24 and 25 respectively to permit of their ready removal and replacement when desired. When the inner member 11 is fully telescoped within the outer member 10 as illustrated in Figure 4, the combined splint has an over-all length equal obviously only to the length of the outer member 10. The inner member 11 may be projected from either end of the outer member 10 and interlocked therewith at any selected point

represented by the spaced pairs of openings 28 in the inner member 11. The configuration of the walls of the outer member 10 and the provision of the tubular side portions 19 and 20 of the inner member 11 provide significant reinforcement for the splint in any position of use. The storage recesses 21 and 22 are readily accessible through the removal of plugs 23 and are conveniently employed for the carrying of syringes, gauze and other first aid equipment. The construction of the splint, with the exception of the interlocking members 24 and 25, lends itself to economic production from molded plastic and like materials.

From the foregoing it will be appreciated that I have provided a flat extensible splint of great simplicity and practicality.

Having thus described my invention, what I claim is:

1. A surgical splint comprising a pair of elongated telescopic members, the inner of said members having a relatively flat transverse web portion and arcuate marginal beads integral with said web portion, the outer surfaces of said beads forming the arcs of circles of substantially greater diameter than the thickness of said web portion; the outer of said members being tubular, relatively flat, and having substantially parallel, spaced, side walls rigidly interconnected by edge walls, said edge walls having inner surfaces which conform in contour to the outer surfaces of the marginal beads of said inner member, the spacing of said side walls being approximately equal to the thickness of the web portion of said inner member.

2. A surgical splint comprising a pair of elongated telescopic members, the inner of said members having a relatively flat transverse web portion and arcuate marginal beads integral with said web portion, the outer surfaces of said beads forming the arcs of circles of substantially greater diameter than the thickness of said web portion, said beads being hollow and providing elongated, cylindrical storage spaces parallel to said bead, with at least one opening at an end of said inner member whereby first aid equipment may be carried in said splint; the outer of said members being tubular, relatively flat, and

having substantially parallel, spaced, side walls rigidly interconnected by edge walls, said edge walls having inner surfaces which conform in contour to the outer surfaces of the marginal beads of said inner member, the spacing of said side walls being approximately equal to the thickness of the web portion of said inner member.

3. A surgical splint comprising a pair of elongated telescopic members, the inner of said members having a relatively flat transverse web portion and arcuate marginal beads integral with said web portion, the outer surface of said beads forming the arcs of circles of substantially greater diameter than the thickness of said web portion; the outer of said members being tubular, relatively flat, and having substantially parallel, spaced, side walls rigidly interconnected by edge walls, said edge walls having inner surfaces which conform in contour to the outer surfaces of the marginal beads of said inner member, the spacing of said side walls being approximately equal to the thickness of the web portion of said inner member; and U-shaped pin means on the device for interlocking said inner and outer members together in telescoped position, said means for interlocking said members embracing a releasable locking element adjacent each end of said outer member, each of said releasable locking elements being independently effective to interlock said inner and outer members with the inner member projected from either end of the outer member.
